UNITED STATES PATENT OFFICE.

JOHN G. CALLAN, OF LYNN, MASSACHUSETTS, ASSIGNOR TO GENERAL ELECTRIC COMPANY,
A CORPORATION OF NEW YORK.

SPEED-CHANGING DEVICE.

No. 869,058.

Specification of Letters Patent.

Patented Oct. 22, 1907.

Application filed June 8, 1904. Serial No. 211,243.

To all whom it may concern:

Be it known that I, JOHN G. CALLAN, a citizen of the United States, residing at Lynn, county of Essex, State of Massachusetts, have invented certain new and 5 useful Improvements in Speed-Changing Devices, of which the following is a specification.

The object of my present invention is the construction of a speed-changing mechanism to be used in connection with a rotating shaft.

10 Where devices such as electric motors are employed for the purpose of driving machinery, it is frequently desirable to use a speed-reducing connection between the device and the machine driven. This is particularly true with electric motors as they are advantageously operated at speeds considerably higher than it is desirable to operate the driven machine.

15 The speed-reducing mechanism which I have hereinafter described and illustrated in detail, is simple and efficient, and when operated in connection with a 20 chain or belt drive can be used as a chain or belt-tightener.

25 The various features of novelty which characterize my invention are pointed out with particularity in the claims annexed to and forming a part of this specification. For a better understanding of my invention, however, reference may be had to the accompanying drawings and description in which I have illustrated and described one form in which my invention may be embodied.

30 Of the drawings, Figure 1 is a perspective view of an electric motor equipped with my speed-changing mechanism; Fig. 2 is a partial section through the motor taken on the line 2 2 of Fig. 3; Fig. 3 is a section taken on the line 3 3 of Fig. 2; and Fig. 4 is a diagrammatic 35 view showing the speed-changing device and a shaft driven thereby through a belt.

36 In the drawings, 1 represents an electric motor of ordinary construction to the left hand face of the casing of which is bolted a member 2. The member 2 is provided with a flange-like portion 3 through which bolts 4 pass into threaded apertures formed for the purpose in the casing of the motor 1 to secure the member 2 in position. The member 2 is also provided with a cylindrical portion or boss 5. The boss 5 may be chambered internally to receive the bearing for one end of the armature shaft 6 of the motor.

40 A member 7 is adjustably secured to the boss 5. The member 7 comprises a circular disk-like portion 8 which may be formed of cast iron, and has formed on its right hand side, as seen in Fig. 2, a semi-cylindrical flange portion 9. A removable arc-shaped piece 10 cooperates with the flange portion 9 to form a split collar which surrounds the boss 5. The member 10 and por-

tion 9 are clamped together by bolts 12 which pass through apertured extensions 9' and 10' formed on the 5 flanged portion 9 and member 10 respectively.

The disk 8 has projecting from its left hand face, as viewed in Fig. 2, a shaft or stud 13. The shaft or stud 13, which is centrally located with respect to the disk 8, has journaled upon it a member 14. The member 14 60 comprises a disk portion 15 and a cylindrical portion 16. The cylindrical portion 16 has gear-teeth 17 formed on its inner periphery.

The end of the motor shaft 6 projects through an aperture formed for the purpose in the disk portion 8 of 65 the member 7 and carries at its end a spur-gear 18, the teeth 19 of which mesh with the teeth 17 of the member 14. The outer surface of the cylindrical portion 16 is recessed at 20 to receive the cylindrical portion of an 70 annular guard 21 which is L-shaped in cross-section as clearly appears in Fig. 2. The radial portion of the guard member 21 serves to retain a dust guard 22 in an 75 annular recess formed for the purpose in the member 7. The dust guard 22 may be formed out of fibrous material or the like. It will be observed that the members 7 and 14 unite to form a chamber or casing which protects and incloses the gear-wheel 18 and co-operating gear-teeth 17.

The outer surface of the portion 16 of the member 14 is convex slightly to form a pulley surface by which a 80 band driving member in the form of a belt may be driven. A sprocket wheel 23 may be keyed on the hub of the member 14, as shown, which may drive a band driving member in the form of a sprocket chain. A nut 24 threaded on the outer end of the stud 13 serves 85 to hold the member 14 in place.

In Fig. 4 I have shown a shaft 25 which is to be driven by a belt 26 which engages the periphery of the cylindrical portion 16 of the member 14. The parts are preferably so arranged that the stud or shaft 13 is substantially between and in line with the shaft 6 and the shaft 25. By adjusting the member 7 about the boss 5 this relation can be obtained with various positions of the motor and shaft 25. Moreover by slightly shifting the member 7 about the boss 5 the stud 13 may be moved 95 to varying distances from the shaft 25, thus affording a means for varying the tension on the belt.

It will be understood that a belt may be driven from the periphery of the cylindrical portion of the member 14 or a shaft may be driven by the sprocket wheel 23, 100 or both drives may be employed at once. Instead of forming the teeth 17 directly on the inner periphery of the cylindrical portion 16 a ring having teeth formed on its inner periphery may be removably secured within the cylindrical portion 16. In place of the sprocket 105 wheel 23 an ordinary pulley may be mounted on the

hub of the wheel 14. The outer periphery of the cylindrical portion of the member 14 may be provided with sprocket teeth if desired.

What I claim as new and desire to secure by Letters

5 Patent of the United States, is,—

1. In combination, a shaft, a support, a member secured to said support and angularly adjustable with respect thereto about said shaft as a center, a rotating member carried by the first mentioned member and eccentrically mounted with respect to said shaft, and a speed-changing driving connection between said shaft and said member.
- 10 2. In combination, a shaft, a support, a member secured to said support and angularly adjustable with respect thereto about an axis which coincides with the axis of said shaft, a rotating power-transmitting member carried by the first mentioned member and eccentrically mounted with respect to said shaft, and a driving connection between said shaft and said rotating member.
- 15 3. In combination, an armature shaft, a casing having a boss or stud formed on it, a gear on said shaft, a second shaft out of line with the first mentioned shaft supported by said boss and angularly adjustable with respect thereto, and a gear wheel carried by said second shaft and meshing with the gear on the armature shaft.
- 20 4. In combination, an armature shaft, a casing, said casing having a boss or stud formed on it concentric to said shaft, a gear on said shaft, a second shaft out of line with the first mentioned shaft carried by the boss and angularly adjustable with respect thereto, a gear wheel carried by said second shaft meshing with the gear on the armature shaft, said gear wheel being formed with a cylindrical portion having gear teeth on its inner surface.
- 25 5. In combination, an armature shaft, a casing provided with a boss or stud concentric to said shaft, a gear on said shaft, a second shaft supported by, but angularly adjustable with respect to said boss, said second shaft being out

of line with the first mentioned shaft, and a gear wheel carried by said second shaft and formed with a cylindrical portion having gear teeth on its inner surface, said gear teeth meshing with the teeth on the gear carried by the 40 armature shaft, the outer periphery of said cylindrical portion being arranged to drive a band.

6. In combination, an armature shaft, a casing, said casing having a boss concentric with the armature shaft, a gear on the armature shaft, a member clamped on said 45 boss but adjustable with respect thereto, a gear wheel journaled on said member, said gear wheel being formed with a web portion and with a cylindrical portion having teeth formed on its inner surface which mesh with the teeth of the gear on the armature shaft, said member and said 50 gear wheel being shaped to form a casing within which the gear on the armature shaft is inclosed.

7. In combination, a shaft, a support, a member arranged to be rigidly secured to said support in different angular relations with respect to an axis which coincides 55 with the axis of said shaft, a rotatable power-transmitting member carried by the first-mentioned member and eccentrically mounted with respect to said shaft, and gearing between said shaft and said rotatable member.

8. In combination, a shaft, a support, a member arranged to be rigidly secured to said support in different angular positions with respect to an axis which coincides with the axis of said shaft, a rotatable power-transmitting member carried by the first-mentioned member and eccentrically mounted with respect to said shaft, and a speed-re- 60 ducing gear between said shaft and said rotatable member.

In witness whereof, I have hereunto set my hand this third day of June, 1904.

JOHN G. CALLAN.
